UNITED STATES PATENT OFFICE.

LEON NANQUETTE, OF PARIS, FRANCE.

STOVE.

Application filed March 31, 1921. Serial No. 457,456.

To all whom it may concern:

Be it known that I, LEON NANQUETTE, a citizen of the Republic of France, and resident of Paris, France, post-office address 19 5 Avenue de Villiers, have invented a new and useful Stove, which apparatus is fully set forth in the following specification.

This invention relates to a continuously burning stove, more particularly intended 10 for burning wood, but in which coke or anthracite coal can also be burned. It is characterized by the combustion being limited to the lower portion of the stove, and by the combustion gases on escaping from 15 the aforesaid lower portion passing into an annular chamber or drum arranged in the upper portion of the stove so as to enable the maximum of the calorific power of the fuel to be utilized.

20 A construction according to the invention is illustrated by way of example in the accompanying drawing in which

Figure 1 is a vertical section of the stove;

Figure 2 is a view partly in elevation and 25 partly in section;

Figure 3 is a horizontal cross-section on line 3—3 of Figure 1;

Figure 4 is a horizontal cross-section on line 4—4 of Figure 1.

30 1 is the casing, preferably of sheet metal, supported by the base 2 resting on the ground by means of feet 3. The casing 1 is lined inside with a refractory earth jacket 4, both the jacket and the casing terminating 35 at about the center of the stove. The lining is removed, however, at the point where the hereinafter-described door and smoke conduit or flue are located. In the base is arranged an ash pit 5, the front part of which 40 has openings 6 for the passage of the air required for the combustion, said openings being controlled by means of a sliding damper. The casing is provided with a door 7 which can be solid or have windows 45 of mica or other similar transparent material. Opposite the door are arranged two vertical deflectors 8 intended to prevent the lighted wood from coming into contact with the door. At the lower end of the casing 50 is arranged a horizontal plate 9 provided with holes and resting on a grate 10. At the front portion of the plate 9 is provided an opening 11 for the passage of the air. At the rear portion of the casing, about 55 the middle of its height, is arranged a cast iron flue 12 forming a smoke conduit afford-

ing passage to the gases going to the heating drum, which latter is indicated generally at 13.

The heating drum is arranged immediately above the casing 1, and is constituted by two concentric cylinders: an inner cylinder 14, preferably of cast iron, forming an extension of the refractory lining, and an outer cylinder 16 which can be of sheet metal 60 or cast iron and which is connected by means of a shoulder to said casing.

Midway between the top and bottom of the drum is arranged a horizontal partition 17 provided with openings 18, 18' (Figure 70 3) so arranged that the gases entering through the conduit 12, pass into the lower annular space, then upwardly through the opening 18 into the upper annular space, and escape through the opening 18' into the 75 smoke outlet 19 which is separated by a diaphragm 26 from the bottom part of the drum. In the inner cylinder 14 are provided openings 20 for the escape of the gases and vapours of distillation, and an opening 21 80 closed by a damper 22, the opening of which gives a direct draft in the smoke outlet.

The drum is surmounted by a top 24 with a sand packing joint 25 carrying the cover 23 which closes the charging opening. 85

The working of the apparatus is as follows: the sticks of wood are introduced vertically into the stove through the upper opening after removal of the cover 23, and they rest on the plate 9. Air enters through the orifices 6 of the ash pit door and passes through the opening 11; the combustion gases escape through the conduit 12. These gases rise, pass into the bottom chamber or compartment of the drum 13 and then 90 through the opening 18 into the upper chamber or compartment thereof, in order to escape from it through the opening 18' and the conduit 19. The distillation gases and steam escape through the holes 20. 95

The draft is regulated by means of the sliding damper of the ash pit door which closes to a greater or less extent the openings 6 and, if necessary, by means of the damper 22 uncovering the opening 21 which 100 accelerates the combustion. The removal of ashes is effected by operating the grate in some suitable manner.

It will be clear from the preceding that the air passes horizontally through the mass 110 of fuel, and that the combustion is limited to the bottom part of the stove, which avoids

any escape of smoke or fumes. Owing to the provision of the drum, the combustion gases give off the greatest portion of their heat, which results in a considerable economy of fuel. By removing the plate 9, the stove could also be used for burning coke or anthracite coal.

What I claim is:

1. In a stove, the combination of a casing having a grate in the lower portion thereof; a lining of refractory material within the casing, said lining having a portion thereof removed to form a vertical flue-receiving space; an annular drum mounted on top of the casing and provided with a cover for closing its open central space; a vertical flue disposed in said flue-receiving space and opening at its lower end into the casing at a point close to the grate, and at its upper end into the bottom of the drum, so as to draw the products of combustion from the fuel on the grate directly into the flue and to discharge them into the drum; means in said drum for causing the products of combustion to travel therethrough in an upwardly-directed spiral path; and an outlet flue communicating with the drum.
2. In a stove, the combination of a casing having a grate in the lower portion

thereof; an annular drum mounted on top of the casing and provided with a cover for closing its open central space; a conduit opening at its lower end into the casing at a point close to the grate, and at its upper end into the bottom of the drum, so as to draw the products of combustion from the fuel on the grate directly into the conduit and to discharge them into the drum; a partition disposed horizontally within the drum midway between its top and bottom and provided with an opening which is located at the opposite side of the drum from the point which said conduit opens thereinto, whereby the products of combustion will be caused to travel through and around the lower part of the drum before reaching said opening and entering the upper part of the drum; and an outlet flue communicating with the drum and disposed on the same side thereof as the conduit.

In testimony whereof I have signed this specification in the presence of two subscribing witnesses.

LEON NANQUETTE.
